FIG. 1.

FIG. 2.

FIG. 3.

FIG. 4.

FIG. 5.

FIG. 1 is a front perspective view of a chair showing my design;

FIG. 2 is a rear perspective view of the chair;

FIG. 3 is a side perspective view of the chair;

FIG. 4 is a perspective view of the chair; and

FIG. 5 is a perspective view of the chair.

The chair of my invention is characterized by a pair of rods converging inwardly from the rear legs of the chair along the back edge of the chair seat, meeting and extending upwardly together to the base of the chair back, and then diverging outwardly to embrace the bottom and side edges of the chair back.

I claim:

The ornamental design for a chair, substantially as shown and described.
